(57) **CLAIM**

The ornamental design for a kiosk as shown and described.

DESCRIPTION

FIG. 1 is a front perspective view of a kiosk showing our new design;

FIG. 2 is a front view thereof;

FIG. 3 is a back view thereof;

FIG. 4 is a left side view thereof;

FIG. 5 is a right side view thereof;

FIG. 6 is an enlarged top plan view thereof;

FIG. 7 is an enlarged bottom plan view thereof;

FIG. 8 is a back perspective view thereof;

FIG. 9 is an enlarged view of portion 9 of FIG. 3;

FIG. 10 is an enlarged view of portion 10 of FIG. 3;

FIG. 11 is an enlarged view of portion 11 of FIG. 3;

FIG. 12 is an enlarged view of portion 12 of FIG. 3;

FIG. 13 is an enlarged view of portion 13 of FIG. 3; and,

FIG. 14 is an enlarged view of portion 14 of FIG. 7.

Dot-Dash broken lines define the boundaries of the enlarged portions and form no part of the claimed design. All other broken lines in the drawing depict portions of the kiosk that form no part of the claimed design. Surfaces shown between the broken lines and the solid lines are included in the claim.

1 Claim, 14 Drawing Sheets
